PROJECTILE GAME APPARATUS

Charles A. McAleer, Miami, Fla.

Application October 24, 1946, Serial No. 705,291

4 Claims. (Cl. 273—108)

1

My invention relates to a manually operated projectile game apparatus.

Important object of the invention is to provide a game apparatus having means to guide the projectiles in their movement so that their paths of travel cross whereby they may collide.

Further object of the invention is to provide a game apparatus having projectiles simulating motor vehicles, and which is interesting to play.

A further object of the invention is to provide a game apparatus having projectiles of different values, thus increasing the interest of the game.

Other objects and advantages of the invention will be apparent during the course of the following description.

In the accompanying drawings forming a part of this application and in which like numerals are employed to designate like parts throughout the same,

Figure 1 is a plan view of the game apparatus embodying my invention;

Figure 2 is a transverse vertical section taken on line 2—2 of Figure 1;

Figure 3 is a central vertical section through the upper and lower projectiles, showing their projections colliding, taken on line 3—3 of Figure 1;

Figure 4 is a longitudinal vertical section taken on line 4—4 of Figure 1;

Figure 5 is a side elevation of one projectile, and,

Figure 6 is a bottom plan view of the same.

In the drawings, wherein for the purpose of illustration is shown a preferred embodiment of my invention, a horizontal support is shown including a rectangular frame 10 having opposed sides 11 and 12. Rigidly mounted upon the sides 11, are equidistantly spaced long vertical posts or pins 13. The posts 13 in one set being in alignment with the posts 13 in the other set. Horizontal suspension elements or wires 14 are attached to the tops of the posts 13. Arranged inwardly of the posts 13 and in alignment therewith are vertical posts or pins 15, rigidly secured to the sides 11. The posts 15 are shorter than the posts 13. Horizontal suspension elements or wires 16 are attached to the tops of the posts 15. The wires 14 and 16 form vertical pairs, and the wires in each vertical pair are in vertical alignment and vertically spaced. The vertical pairs of wires are equidistantly spaced. Vertical long outer posts or pins 17 are rigidly secured to the sides 12, and these posts are equidistantly spaced, and the posts 17 in one set are in alignment with the posts 17 in the other set. The posts 17 are longer than

the posts 13 and extend above the posts 13 and are connected by upper horizontal suspension elements or wires 18, arranged above and spaced from the wires 14. Disposed inwardly of the posts 17 are vertical posts 19, in alignment with the posts 17 and the posts 19 are shorter than the posts 17, but are longer than the posts 13. The posts 19 in the opposite sets are in alignment. The posts 19 are connected by horizontal suspension elements or wires 20. The wires 18 and 20 form vertical pairs and the wires 18 and 20 in each pair are in alignment and vertically spaced. The pairs of wires 18 and 20 are at an elevation well above the vertical pairs of wires 14 and 16. The pairs of vertically spaced wires 14 and 16 are at right angles to the pairs of vertically spaced wires 18 and 20.

Mounted to slide upon the pairs of wires 14 and 16 are projectiles 21, having the design or shape of a motor vehicle, such as an automobile or truck. These projectiles are preferably formed of rubber, plastics, or the like, and are preferably solid. Each projectile has longitudinal openings 22 formed therein at its transverse center and near its top and bottom, to slidably receive the wires 14 and 16. Each projectile 21 is provided at its top end at its transverse and longitudinal centers with reduced projections 23, formed integral therewith, and extending above the projectile for a substantial distance. The projectiles 21 may be of different colors and may have different values. Similar projectiles 24 are slidably mounted upon the wires 18 and 19 and have longitudinal openings 25 to receive the wires 18 and 20. Each projectile 24 is provided at its bottom with a depending reduced projection 26, at its longitudinal and transverse centers. The projection 26 is integral with the projectile 24. Each projectile 24 has a design or appearance of a motor vehicle such as an automobile or truck, and these projectiles may be of different colors and may have different values. The projectiles 24 are supported at an elevation above the projectiles 21 whereby the projectiles 24 and their projections

26 will clear the projectiles 21 but the projection 26 may move into the path of travel of the projection 23 and collide therewith. Also, the projectile 21 and its projection 23 will clear the projectile 24, but the projection 23 may collide with

the projection 26.

Horizontal rods 27 are provided, disposed at an elevation above the posts 17, and arranged outwardly of the outer pairs of wires 14 and 16. These rods are supported by vertical extensions 28, rigidly mounted upon the sides 11. Horizontal

tal rods 29 are secured to the rods 27 and are arranged outwardly of the outer pairs of wires 18 and 20. The rods 27 and 29 are arranged inwardly of the vertical posts and inwardly of the projectiles where the projectiles are in the starting position. These rods 27 and 29 form a rectangular guard, to limit the inward movement of the hand or finger in playing the game.

In use, one player is located at the side 11 and the other player at the side 12. The player at the side 11 selects a projectile 21 and strikes it with the forefinger, causing it to travel rapidly forwardly upon the wires 14 and 16. The player at the side 12 strikes a selected projectile 24 and attempts to cause the projection 26 to collide with the projection 23 of the thrown projectile 21. If a collision occurs between the projections 23 and 26 the player at the side 12 would win the point. The value of the point won could depend upon the values of the two projectiles in the play. If the projections of the projectiles collide, these projectiles are cleared by shifting them to the free ends of the wires, before the next play. Upon the next play, the player at the side 12 will strike the projectile with the forefinger, and the player at the side 11 will strike his projectile and attempt to cause a collision. Various suitable rules may be provided for the playing of the game.

It will be seen that the pairs of vertical spaced wires accurately guide the projectiles during their travel. This will prevent the turning movement of the projectiles so that their projections may collide.

It is to be understood that the form of my invention herewith shown and described is to be taken as a preferred example of the same and the various changes in the shape, size, and arrangement of parts may be resorted to without departing from the spirit of my invention or the scope of the subjoined claims.

Having thus described my invention, what I claim is:

1. A game apparatus comprising, a support, spaced pairs of substantially horizontal suspension elements, the suspension elements in each pair being vertically spaced, means to support the pairs of suspension elements, spaced pairs of substantially horizontal suspension elements arranged above the first named pairs of suspension elements and disposed at generally right angles to the same, the suspension elements in each upper pair being vertically spaced, means to support the upper pairs of suspension elements, projectiles having longitudinal openings to receive the lower pairs of suspension elements, projectiles having longitudinal openings to receive the upper pairs of suspension elements, upwardly extending projections carried by the lower projectiles, depending projections carried by the upper projectiles, the upper projectiles being arranged to clear the lower projectiles and their projections and the lower projectiles be-

ing arranged to clear the upper projectiles and their projections, the projections of the upper and lower projectiles being arranged to travel at a common elevation.

5 2. A game apparatus comprising, a support, spaced pairs of substantially horizontal suspension elements, the suspension elements in each pair being spaced, means to support the pairs of suspension elements, spaced pairs of substantially horizontal suspension elements arranged above the first named pairs of suspension elements and crossing the same, the suspension elements in each upper pair being spaced, means to support the upper pairs of suspension elements, projectiles having openings to receive the lower pairs of suspension elements, projectiles having openings to receive the upper pairs of suspension elements, projections carried by the lower projectiles, projections carried by the upper projectiles and arranged so that they may collide with the projections of the lower projectiles.

25 3. A game apparatus comprising, a support, spaced substantially horizontal suspension elements, a second set of spaced substantially horizontal suspension elements arranged at a different elevation with relation to the first set of suspension elements and crossing the same, means to support the two sets of suspension elements, projectiles mounted upon one set of suspension elements and each simulating a motor vehicle and having a reduced projection, projectiles mounted upon the second set of suspension elements and each simulating a motor vehicle and having a projection arranged to collide with the first named projections.

40 4. A game apparatus comprising, a support, spaced substantially horizontal suspension elements, a second set of spaced substantially horizontal suspension elements which cross the first set of suspension elements and are vertically spaced therefrom, projectiles mounted upon the first set of suspension elements and each simulating a motor vehicle, projectiles mounted upon the second set of suspension elements and each simulating a motor vehicle, projections carried by the first set of projectiles, projections carried by the second set of projectiles and constructed and arranged to cooperate with the first named projections, and a guard arranged near the suspension elements to limit the inward movement of the hands or fingers of the players.
